UNITED STATES PATENT OFFICE

149,959

DESIGN FOR AN ADJUSTABLE LOUNGE
CHAIR

Frank J. Luketa, Seattle, Wash.

Application March 26, 1946, Serial No. 127,959

Term of patent 14 years

(Cl. D15—1)

To all whom it may concern:

Be it known that I, Frank J. Luketa, a citizen of the United States of America, residing at Seattle, in the county of King and State of Washington, have invented a new, original, and ornamental Design for an Adjustable Lounge Chair, of which the following is a specification, reference being had to the accompanying drawing, forming part thereof.

able lounge chair, with its parts in substantially the positions of adjustment which are shown in Figure 3.

I claim:

The ornamental design for an adjustable lounge chair, substantially as shown.

FRANK J. LUKETA.
